WILLIAM B. JARVIS, OF GRAND RAPIDS, MICHIGAN, ASSIGNOR TO W. B. JARVIS
COMPANY, OF GRAND RAPIDS, MICHIGAN

DESIGN FOR A LATCH HANDLE

Application filed July 28, 1930. Serial No. 36,496. Term of patent 7 years.

To all whom it may concern:

Be it known that I, WILLIAM B. JARVIS, a subject of the King of Great Britain, residing at Grand Rapids, in the county of Kent and State of Michigan, have invented a new, original, and ornamental Design for a Latch Handle, of which the following is a specification, reference being had to the accompanying drawing, forming part hereof.

Fig. 1 is a front elevation, Fig. 2 a plan view, and Fig. 3 an end view of a latch handle embodying my new design.

I claim:

The ornamental design for a latch handle as shown.

WILLIAM B. JARVIS.
